UNITED STATES PATENT OFFICE.

GOUVERNEUR G. BROWN, OF NEW YORK, AND PAUL A. SCHUCHART, OF ROCKVILLE CENTER, NEW YORK, ASSIGNEES TO PAPER SERVICE COMPANY, A CORPORATION OF NEW YORK.

SHEET-INTERFOLDING MACHINE.

1,348,846.

Specification of Letters Patent. Patented Aug. 10, 1920.

Application filed September 28, 1916. Serial No. 122,591.

To all whom it may concern:

Be it known that we, GOUVERNEUR G. BROWN and PAUL A. SCHUCHART, citizens of the United States, residing at New York city, county of Kings, State of New York, and Rockville Center, county of Queens, State of New York, respectively, have invented certain new and useful Improvements in Sheet-Interfolding Machines, fully described and represented in the following specification and the accompanying drawings, forming a part of the same.

This invention relates to improvements in sheet interfolding machines:

The objection to such machines as heretofore known has been the difficulty in obtaining a satisfactory product in commercially satisfactory quantities.

It is the object of the present invention to provide a sheet interfolding machine that effectively cuts, feeds and interfolds the sheets and operates at such a high rate of speed as to turn out a satisfactory product in larger quantities than has heretofore been possible, and, further, one that delivers these interfolded sheets compressed and packed into a compact stack, thereby both improving the product and lowering the cost of production.

The following specification describes, and the accompanying drawings illustrate, a preferred embodiment of the invention, it being understood that changes may be made in the form, construction and arrangement of the parts without departing from the invention.

In the drawings—

Figure 1 is an end elevation of a sheet interfolding machine constructed in accordance with the present invention;

Fig. 2 is a cross-sectional view taken on the line 2—2 of Fig. 1, looking in the direction of the arrow;

Fig. 3 is an enlarged view showing in detail a portion of Fig. 2, and

Fig. 4 is a detail view showing one of the friction rollers.

The invention includes means for transversely creasing and cutting a plurality of webs in such a manner that the sheets so formed when brought together overlap with the crease of one series alining with the adjoining edges of the sheets of the opposite

series. This may be accomplished by various constructions. In the form of the invention illustrated, referring to the drawings, two webs of paper are indicated by dotted lines 5. Following the course of one of these, for example the one on the right in Fig. 2, it passes down under a friction roll 6 to the periphery of a large feeding cylinder 7, carried by a shaft 8, driven as herein-after described, the housing of which is supported by the main frame 9. Associated with this cylinder is a smaller cylinder 10 rotated in the opposite direction by a shaft 11, the housing of which is also supported by the frame 9. The web feeds down between these two cylinders to be cut and creased at their common tangential point. Carried by the large cylinder are four transverse creasing ribs 13 formed of suitable material and located on equally spaced radii which, as the cylinders rotate, enter transverse V-shaped recesses 14 formed in the small cylinder and filled with rubber, to crease the web as it is fed. The small cylinder also carries two cutting blades 12 located half way between the V-shaped recesses which enter cutting blocks 15 carried by the large cylinder 80 and located half way between the creasing ribs to cut the web, thereby forming sheets creased across the middle. There are four of these cutting blocks and four creasing ribs on the large cylinder and two cutting blades and two creasing recesses on the small cylinder. The large cylinder rotates once for two revolutions of the smaller one, so that for every revolution of the large cylinder, four creased sheets are cut from the 90 web.

The invention includes means for placing the web, while being fed to the cutters, under tension transversely as well as longitudinally, in order to avoid wrinkling and the like. In constructions embodying the invention to the best advantage, this is attained by means tending to pull the web from the middle outwardly. Such means is capable of a variety of constructions. In the present embodiment the friction rolls 6 are wound with some yielding material, such as felt, in two opposite spirals starting at the middle and spiraling toward each end. As a result of this construction, the web 105 is pressed out flat and kept under trans-

verse tension, and at the same time the course of the web is not interfered with, as the tensioning influence is equal toward each edge.

5 The invention includes means for coöperating with the large cylinder to feed the sheets as far around the cylinder as desired, as for example, the bottom point of its path. While this may be accomplished in various ways, in the exemplification shown, a plurality of endless feeding chains 16 (three being illustrated) are driven in the same direction as the cylinder and, with the latter, feed the web ends and the sheets as they are received from the cutters. These chains pass over grooved idlers 17 located not far from the cutting point and they are held up against the cylinder by a second set of grooved idlers 18, as shown in Fig. 2.

10 20 Means are provided for coöperating with the large cylinder to feed the successive web ends from the cutting point to the point where the chains 16 take hold, thereby to prevent "floating."

15 25 While such means may be of various constructions, in the embodiment shown the small cylinder carries, just back of each cutting blade, a plurality of fingers 19 extending almost from end to end of the cylinder, 30 the cylinder being provided with a suitable recess therefor. These fingers are mounted on a rock shaft 20 which has at one end an arm 21 carrying a roller 22 which travels over a cam 23. This cam is so designed that, 35 just after a cut has been made in the web, the arm 21 is operated to rock the shaft 20 and throw out the fingers to coöperate with the large cylinder in feeding the successive web ends onward until they reach 40 the chains 16. As the small cylinder continues to rotate the cam causes the fingers to be withdrawn within the cylinder. In order to hold the web ends against the large cylinder, between the cutting point and the

45 50 point where the chains 16 take hold, in case the cam is not adjusted properly, and to prevent the web ends from following the withdrawing fingers due to the possible presence of static electricity, there is provided 55 a plurality of stationary guides 24, under which the successive web ends pass. In order to have the fingers operate at the proper instant, in case, for example, the axis of the smaller cylinder is shifted to accommodate different thicknesses of paper, the cam is made adjustable. Extending out from the cam is a lug 25 through which is threaded an arm 26 pivotally connected to the frame of the machine. Above and below 60 the lug are nuts 27, and by unloosening these nuts to swing the arm 26 slightly, the cam position is adjusted to retard or advance the action of the fingers as desired.

65 Beyond the idlers 18 the feeding chains leave the large cylinder and pass over idlers

36 which direct the chains obliquely downward. Coöperating with the chains 16 in feeding the sheets onward, are a series of supplemental chains 29 passing over upper grooved idlers 30 and lower sprockets 31 70 driven as hereinafter described. The idlers 30 are located just above the idlers 36, so that the latter act on both sets of chains to change the direction of their common paths.

75 Means are provided for coöperating with the chains 16 to feed the sheets from the time the cylinder leaves them until they reach the supplemental chains 29, thereby to prevent floating. While this may be accomplished by various constructions, that which is illustrated is similar to the mechanism already described, and comprises a plurality of fingers 32 carried by a rock shaft 33 in the large cylinder, a suitable recess being provided therefor, the shaft having an 80 arm 34 carrying a roller which travels on a cam 35. As there are four sheets cut for each revolution of the cylinder, there are four sets of these feeding fingers and the fingers are so located and the cam so designed that, as the cylinder leaves the chains 16, the fingers are thrown out and serve to hold each succeeding sheet down against the chains 16 and in cooperation with the latter to feed the sheets onward, substantially to 85 the supplemental chains. Stationary guides 28 serve to hold the sheets against the chains 16 and to prevent the sheets from following the fingers when the latter are withdrawn.

90 95 Below the sprockets 31 are stationary triangular guides 37, at the points of which the chains 16 pass over sprockets 38 carried by cross-shafts 45 and 70, respectively, and then pass upward to the idlers 17, thus completing their cycle.

100 105 Means are provided for adjusting the tension of the chains 16 on their upward inactive course. Although capable of various constructions, the means illustrated include, for each chain, a tension pulley 39 suspended by arm 40 from a rock shaft 41. Mounted on this shaft are arms 42 having pivotal connection with rods 43 threaded through lugs 44 carried on the main frame and locked in position by suitable nuts. By loosening the nuts and shifting the position of the rods 43, the tension pulleys 39 are raised or lowered to loosen or tighten the chain.

110 115 The mechanism for cutting, creasing and feeding the other web is precisely similar to that above described, except for the relative position of the cutting blades, creasers, and the swinging fingers. These are arranged so that when one web is being creased, the other is being cut and vice versa; and as the cutters on each cylinder are half way between the creases, it will be seen that when the sheets are brought together at the point of the triangular guides 37, they are overlapped, the adjoining ends 120 125 130

of two sheets of one set being alined with the crease of the sheet of the opposite set.

The invention includes means for inter-folding these overlapped sheets and delivering them to feeding and stacking apparatus. This may be done in various ways. In the embodiment illustrated, the overlapped sheets are taken from the two sets of chains 16 by two sets of feeding and interfolding 5 chains 46 and 47, there being shown three chains in each set. These chains feed the sheets downward and at the same time oscillate, as hereinafter described, to interfold the same. The chains 46 and 47 are driven 10 by sprockets on the shafts which drive the sprockets for the feed chains 16, so that there is no break in the feed as the sheets pass from one series of chains to the other. At their lower ends, the chains 47 pass over 15 idlers carried by a cross-shaft, 48, and the chains 46 pass over idlers carried by a cross-shaft 49. The shaft 49 is suspended from arms 50 and the shaft 42 by arms 51. To oscillate these chains, the shaft 48 is pivoted at 20 each end in a link 52, which is eccentrically connected to a pinion 53 driven as hereinafter described. The arms 51 carry at their lower end an extension having a slot formed therein, in which the shaft 49 rides as the chains 25 are swung to and fro. Located just below the path of these swinging chains are two pair of sheet-receiving spirals 54. These spirals are of suitable spring material secured to vertical shafts 50, the shafts of 30 each pair being rotated in opposite directions, as hereinafter described.

The interfolding of the sheets by the oscillating chains and the reception of the sheets by the spirals is clearly shown in Fig. 3. As 35 the chains reach the end of one oscillating stroke and start back on the next they fold the outside sheet along its crease, thus causing it to inclose the ends of the two opposite sheets, the continued oscillation of the chains 40 interfolding the sheets continuously as long as they are fed. The spirals are so designed and so rotated that, as the oscillating chains make a fold, the first coil advances and passes over the fold to hold the sheets, until, 45 when the chains have returned to make another fold, the first unit is completely embraced between the coils and the top coil is ready to receive another unit.

The invention includes means for compressing and packing the interfolded sheets into a compact stack. While this may be accomplished in various ways, in the form shown, the spiral feeds are so constructed 50 that the spaces between the coils gradually diminish so that the coils are closer and closer together. As the sheets feed downward, these gradually closing coils squeeze out the air to the sides and complete and flatten the fold, each crease being wiped 55 from the center toward the ends, thereby

preserving a true relation of the sheets. This action of the coils serves to compress the sheets, face to face, into a compact stack, and at the same time the stack is being made compact edgewise. It has been found that 70 in interfolding machines the ends of the two interfolded sheets are not completely up into the crease of the overfolding sheet, so that the pack is wider and looser than is desirable. In the present exemplification of 75 means for making the pack compact, the shafts of the spirals are constructed to act on the units edgewise to pack them together, and at the same time to so act without buckling of the sheets and the like. Near 80 the tops, these shafts are of a size to allow clearance for the sheets even in the slightly loose condition noted. As shown clearly in the left hand spiral of Fig. 2, the shafts are constructed with a frusto-conical portion, so 85 that the clearance gradually lessens and the edges of the sheets are acted on by the revolving shafts, so that the pack is gradually pressed together to make a compact 90 stack.

As these interfolded sheets reach the bottom of the spirals, they drop out by gravity and pass down the curved chute 56 until they assume a vertical position and reach the delivery belt 57. It is ordinarily desirable, when starting the machine, either to 95 fill the chute with past product or hold the newly delivered sheets until the chute is filled, so that the units first delivered will not separate. It will be noted that, as long 100 as the machine feeds the webs, there is an unbroken delivery of interfolded sheets, and this "chain" may be broken at such points on the delivery belt as desired, merely by grasping a bundle of sheets and pulling out 105 the flap of the last sheet. It may be desirable to remove uniform bundles for use in dispensing apparatus and the like, and the invention includes means for marking the interfolded units in counted bundles of any 110 desired size to indicate where the removal is to be made. While this may be accomplished in various ways, in the embodiment shown, on the end of shaft 74 which drives two of the spirals is a bevel gear 101 meshing with a similar gear 102 on a shaft 103 which has at its opposite end a worm 104 meshing with a gear 105 on a cross shaft 106. Pinned to this shaft, so as to be midway between two of the spirals, as clearly 115 appears in Fig. 1, is an arm 107 carrying at its end a marking pad 108, which is inked in any suitable manner. As the spirals revolve to feed the units downward, the arm 107 also revolves and at regular intervals 120 brings the marking pad in contact with the edges of two adjacent units, thus marking the end and beginning of a bundle. It is noted that the marker arm is driven at a 125 fixed speed with respect to the spiral units, 130

so that for every revolution of the marking arm, the spirals have rotated a given number of times, thus advancing a given number of sheet units. Consequently, the same 5 number of units pass for each revolution of the arm and the same sized bundles are marked each time. The size of the bundles, that is to say the number of sheet units between marks, is governed by the speed ratio 10 between the spirals and marking arm, and by changing the relation of the driving gear, the arm may be driven at any given relative speed to mark the units and bundles of any desired size. Since the individual 15 units are embraced between the coils of the spiral feeds, and since the speed of the counter is fixed with respect to the speed of the spirals, the units are always properly marked regardless of the thickness 20 of the paper used. It is noted that the first and last unit of each bundle is marked so that it can be readily discovered if a few units become dislodged from a bundle after removal.

25 The various driven parts of the machine are operated as follows:

A main power shaft 58, which has its bearing in the main frame 9, carries at its end a bevel gear 59 meshing with a similar 30 gear 60 on an oblique shaft 61. The latter drives a bevel gear 62, on the shaft of which is a pinion 63 meshing with a large gear 64 on the shaft 8 of the right hand large cylinder 7. This large gear 64 in turn meshes 35 with a pinion 65 on the shaft 11 of the right hand small cylinder 10. The pinion 63 also meshes with a pinion 66 which drives a large gear similar to gear 64 on the shaft of the left hand large cylinder, this in turn driving 40 a pinion on the shaft of the left hand small cylinder. The gear for the left hand large cylinder drives a pinion 67, on the shaft of which is a pinion 68 driving a gear 69 which meshes with a pinion on shaft 70. 45 This shaft is the one, before referred to, which drives the sprockets for left hand chains 16 and the chains 47. On this shaft 70 is also a gear driving a gear on shaft 45, which carries the sprockets for the right 50 hand set of chains 16 and the chains 46. From the gear just mentioned on shaft 45, a train of gears 71 drives the shafts for the sprockets 31 of the supplemental chains 29. The main drive shaft 53 carries two gears 55 72 meshing with the pinions 53 which operate the links 52 for oscillating the swinging chains. The main drive shaft 53 also drives a chain 73 which drives a shaft 74. On this shaft are two miter gears 75 which mesh 60 with miter gears 76 on the shaft 55 of the two spiral feeds shown in Fig. 1. Shaft 74, which also carries a sprocket 77, drives a chain 78, which, through a sprocket, drives shaft 79 which carries two miter gears 80 65 meshing with miter gears 81 on the shafts

55 of the other two spiral feeds. The delivery belt is driven in any suitable manner, and no further description is necessary.

It is thought that the operation of the machine will be clear from the foregoing 70 description. It is noted that, due to the general construction of the device, practically all of the parts are readily accessible. The large cylinders are separated by a substantial distance, the supporting frame is 75 open at the ends and the greater part of the driving gearing is outside this frame, and the construction which permits the four cams to be adjusted also permits them to be moved out of the way to give access to the 80 ends of the four cylinders. It is also noted that, due to the construction described, there is substantially no gap in the feed, there being a continuous hold on the web ends and sheets, thereby eliminating floating and its 85 attendant disadvantages.

What is claimed is:

1. In combination with apparatus for creasing a plurality of webs and cutting the webs into sheets and bringing the sheets together in overlapped relation, means for interfolding the sheets, and a plurality of 90 rotating spring spirals for receiving said interfolded sheets and feeding them away from the folding means. 95

2. In combination with apparatus for creasing a plurality of webs and cutting the webs into sheets and bringing the sheets together in overlapped relations, means for interfolding the sheets, and a plurality of 100 spirals for receiving the interfolded sheets and feeding them away from the folding means, some of the coils of said spirals being closer together than the others.

3. In combination with apparatus for 105 creasing a plurality of webs and cutting the webs into sheets and bringing the sheets together in overlapped relation, means for interfolding the sheets, and a plurality of 110 spirals for receiving the interfolded sheets and feeding them away from the folding means, the coils of said spirals being closer together at the delivery end than at the receiving end.

4. In combination with apparatus for 115 creasing a plurality of webs and cutting the webs into sheets and bringing the sheets together in overlapped relation, means for interfolding the sheets, and a plurality of 120 spirals for receiving the interfolded sheets and feeding them away from the folders, the space between the coils of said spirals gradually decreasing.

5. In combination with apparatus for 125 creasing a plurality of webs and cutting the webs into sheets and bringing the sheets together in overlapped relation, means for interfolding the sheets, and means for pressing each individual interfolded unit by a wiping action, along the folded edge thereof.

6. In combination with apparatus for creasing a plurality of webs and cutting the webs into sheets and bringing the sheets together in overlapped relation, means for interfolding the sheets, and means for pressing each individual interfolded unit, the pressure being applied from the middle toward each end simultaneously. 5
7. In combination with apparatus for creasing a plurality of webs and cutting the webs into sheets and bringing the sheets together in overlapped relation, means for interfolding the sheets, and means for pressing each individual interfolded unit with 10 gradually increasing pressure. 15
8. In combination with apparatus for creasing a plurality of webs and cutting the webs into sheets and bringing the sheets together in overlapped relation, means for interfolding the sheets, and means for subjecting the interfolded sheets to pressure on the edges thereof. 20
9. In combination with apparatus for creasing a plurality of webs and cutting the webs into sheets and bringing the sheets together in overlapped relation, means for interfolding the sheets, and means for subjecting the edges of the interfolded units to gradually increasing pressure. 25
10. In combination with apparatus for creasing a plurality of webs and cutting the webs into sheets and bringing the sheets together in overlapped relation, means for interfolding the sheets, a plurality of spirals 30 for receiving the interfolded sheets and feeding them away from the interfolding means, and means for subjecting the edges of the interfolded units to edgewise pressure while passing through said spirals. 35
11. In combination with apparatus for creasing a plurality of webs and cutting the webs into sheets and bringing the sheets together in overlapped relation, means for interfolding the sheets, a plurality of frusto-conical members, and means for feeding the interfolded sheets past said members, so as to come in contact therewith. 40
12. In combination with apparatus for creasing a plurality of webs and cutting the webs into sheets and bringing the sheets together in overlapped relation, means for interfolding the sheets, and a plurality of spirals for receiving the interfolded sheets and feeding the same away from the interfolding means, the shafts of said spirals each 45
- having a frusto-conical portion situated to come in contact with the interfolded units fed by the spirals. 50
13. In sheet interfolding apparatus, creasing and cutting cylinders for each of a plurality of webs, between which the webs are fed, and means for bringing the sheets together for interfolding, such that the advance portions of the web and the several sheets are at all times positively fed and the sheets are subjected to substantially continuous feed from said cutting point to the interfolding point. 55
14. In a sheet interfolding machine, a plurality of rotating spirals for delivering the interfolded units, a revolving marker for marking the edges of two adjacent units, and means for revolving said marker at a given ratio to the speed of said spirals. 60
15. The combination with a plurality of rotating spirals for feeding sheets, of means, operated at a given ratio with respect to the speed of said spirals, for marking said sheets to denote bundles of given numerical size. 65
16. In a sheet interfolding machine, means for feeding the interfolded units in separated relation, a marker movable into a position to mark the interfolded units while in said feeding means, and means for operating said marker at a speed in a given ratio to the speed of said feeding means. 70
17. In a sheet interfolding machine, two open-ended side frames, two cylinders spaced a substantial distance apart, over which the webs pass in opposite directions, two cylinders coöperating therewith to feed, cut and crease the webs, driving gears in alinement with said cylinders at one end thereof, cams in alinement with said cylinders at the other end, and means whereby said cams are movable out of the way to give access to the ends of said cylinder. 75
18. In combination with apparatus for creasing a plurality of webs and cutting the webs into sheets and bringing the sheets together in overlapped relation, means for interfolding the sheets, means for pressing the interfolded units along the edge thereof, and means for applying pressure against the folded edges. 80
- In witness whereof we have hereunto signed our names. 85

GOUVERNEUR G. BROWN.
PAUL A. SCHUCHART.
